CLAIM

The ornamental design for a combined building and walkway, as shown and described.

DESCRIPTION

FIG. 1 is a perspective view of a combined building and walkway showing my new design;
FIG. 2 is a front elevational view thereof;
FIG. 3 is a rear elevational view thereof;
FIG. 4 is a top view thereof with the entrance walkway of FIGS. 1 and 2 removed for clarity; and,
FIG. 5 is a side elevational view with the opposite side being a mirror image thereof, the entrance walkway of FIGS. 1 and 2 being removed for clarity.
The undisclosed bottom is unornamented.

FIG. 1**FIG. 2**

FIG. 3**FIG. 4**

FIG. 5
